CLAIM

I claim the ornamental design for a corrugated tube clamp, as shown and described.

DESCRIPTION

FIG. 1 is a perspective view in an opened position showing our new design;

FIG. 2 is a perspective view in a clamped position thereof;

FIG. 3 is a top plan view in a clamped position (3) thereof;

FIG. 4 is a sectional view of the clamp of FIG. 6 in a clamped position (1);

FIG. 5 is a sectional view of the clamp of FIG. 6 in a clamped position (2); and,

FIG. 6 is a sectional view in a clamped position (3) thereof, taken at line 6-6 of FIG. 3.

The broken lines shown in the drawings represent unclaimed portions of the corrugated tube clamp and form no part of the claimed design.
